UNITED STATES PATENT OFFICE.

ALVA C. STEIN, OF WORTHINGTON, OHIO.

LIFTING-JACK.

1,099,405.

Specification of Letters Patent.

Patented June 9, 1914.

Application filed June 20, 1913. Serial No. 774,763.

To all whom it may concern:

Be it known that I, ALVA C. STEIN, a citizen of the United States, residing at Worthington, in the county of Franklin and State 5 of Ohio, have invented certain new and useful Improvements in Lifting-Jacks, of which the following is a specification.

The present invention relates to improvements in lifting jacks, and is designed especially for use in raising and re-railing or 10 replacing de-railed railway cars.

While the invention is herein referred to as used in connection with street railways and that type of cars, it will of course be 15 understood that the invention is equally applicable for use in connection with other vehicles, whether the motive power is carried by the vehicle, or applied from an extraneous source.

20 The primary object of the invention, as will be readily understood, is to provide each vehicle with an efficient means, operated from a self-contained source, for the rapid and facile restoration to the railway track of a derailed car.

25 The invention consists in certain novel combinations and arrangements of parts, carried by the car and normally out of operation, by which the derailed car may be 30 lifted vertically from the ground and then shifted laterally into alignment with the rails, and lowered directly onto the rails, and these operations are accomplished through devices actuated from motive power 35 carried by the car.

40 In the accompanying drawings I have 45 illustrated one complete physical embodiment of my invention applied to an electric car and constructed according to the best mode I have so far devised for the practical application of the principles of the invention.

In the drawings:—Figure 1 is a cross section of a car (conventionalized) showing in 50 side elevation my invention applied thereto, the car in proper position on the rails, and the lifting jack out of commission. Fig. 2 is a plan view of the underside of the working parts of the device, the motor, and the bases of the jacks being omitted for convenience of illustration. Fig. 3 is an enlarged detail view showing the underside of a portion of Fig. 2, with a portion of the motor illustrated and its connected gearing. 55 Fig. 4 is a side elevation of a fragment of a street railway car to illustrate the position

of the lifting jack between the end of the car and its traction wheel. Fig. 5 illustrates a derailed car, lifted from the ground by the jack and ready to be shifted laterally. Fig. 6 illustrates the same car shifted to the lateral limit of the jack; to properly replace the car it must again be lowered, the jacks shifted, the car again raised, and then shifted until the wheels aline with the rails. Fig. 7 is an enlarged transverse section, showing a shifting roller, its support and its track. Fig. 8 is a similar view showing the fixed nut. Fig. 9 is an enlarged detail of the vertical adjusting mechanism of the 70 jack.

In the preferred embodiment of my invention I have illustrated the lifting jack in connection with an electric car A having the usual wheels B and axle C, and the wheels 75 are adapted to run in the grooved rails D of suitable or usual type. While only one lifting jack is illustrated, at the end of a car, it will be understood that a car may be equipped with a lifting jack at each end if 80 desired, and the location of the jack may also be varied to suit circumstances, construction of cars, framing, etc.

In equipping cars with my invention, I utilize a metallic plate 1 which is rigidly 85 secured to the underside of the car and extends transversely thereof. The plate may be bolted to the underframing or beams of the car, and is held immovable in relation thereto. A series of perforated ears 2 are 90 located at each side of the plate 1. These ears are perforated and at their lower ends formed with lugs 3, the whole being integral with the plate 1. The perforated ears are arranged in pairs and are designed to afford 95 a bearing for the pintles 4 of a series of rollers 5. Approximately midway its length the plate is provided with an integral lug 6, perforated and threaded, and of sufficient size and strength to perform the function 100 of a fixed nut in connection with a screw bar 7. This screw 7 is supported from a beam 8, preferably of metal, through the agency of a pair of perforated bearing lugs 9 integral with the beam and depending 105 from the underside thereof. The plate 1 and beam 8 are relatively movable, and the beam is located under the rollers 5 so that they may travel over the upper surface of the beam, side flanges 10 on the beam 110 coacting with the lugs 3 of the plate to confine and guide the movement of the parts.

The fixed nut 6 on the plate 1 projects through a center slot 11 in the beam and this slot is long enough to permit necessary movement of the parts *i. e.* the beam and plate with relation to each other. When the lifting jack is in operative position the beam 8 is suspended on a pair of pedestals 12, 13, each of which is provided with a screw bar 14, 15. These screw bars 10 are moved through the medium of gear or worm wheels 16 and 17 which are located between the ends of the beam and a perforated bearing bracket 18, 18, integral with the beam and located directly below the perforated end thereof, so that the worm wheels are confined and revolve between the end of the beam and one of the brackets. The worm gears may be revolved independently, and each one has an actuating 15 bar as 19 and 20 with a worm 21 and 22, the worm 21 engaging the wheel 16 and worm 22 engaging the wheel 17. These bars are supported at the underside of the beam in bearing lugs 23 and each bar is equipped 20 with a driving gear as 24, 25. In Fig. 3 it will be seen that the screw-bar 7 also has a gear wheel, 26, and these three wheels 24, 25, and 26 are located in position to mesh with a long gear 27 in the driving shaft 28 25 of the motor 29. The motor 29 is secured at the underside of the beam, and is thus in position to supply motive power for operating the devices to lift the car vertically and also to shift it, after being lifted to 30 proper height, laterally. Shifting rods 30, 31, 32, are provided for shifting the several gear wheels into or out of mesh with the long gear on the motor shaft, and for convenience these rods may be operated from the 35 same side of the car. In Fig. 3 it will be seen that the worm wheels on the vertical screw bars may be actuated simultaneously, or either of them may be actuated independent of the other. If required the vertical screw bars may extend up through openings in the car floor, in a location where they will not interfere with other arrangements 40 of parts of the car.

From the above description taken in connection with the drawings the operation of 50 the device is evident. Should a car become derailed, the current is turned into the motor 29 and the gears 24, 25 are moved to engage motor gear 27 in order to lower the pedestals of the jacks. If the surface is 55 irregular or uneven, one of the jacks may be lowered below the other. When the pedestals are in proper supporting position, the motor is reversed, and the car is raised or lifted by the described connections sufficiently to permit the bodily shifting of the car. The two gears 24 and 25 are now shifted 60 out of mesh and the gear 26 is shifted into engagement with the gear 27. The motor now turns the screw bar 7 and by its 65 engagement with the threaded, fixed nut 6 of the plate 1, the car is shifted until it reaches a position with the wheels over the rails. The lateral shift is then cut out, and the lowering devices are brought into operation, the motor and gear connections being again utilized to lower the car to the 70 tracks. After the car is replaced, the jack pedestals are raised into normal position, 75 as shown.

Having thus fully described my invention, what I claim as new and desire to secure by Letters Patent is:—

The combination with a car and permanently fixed plate extending from side to 80 side thereof and having an integral nut, perforated ears, rollers in the ears and guide lugs on the ears, of a beam supporting the plate through the rollers, a screw bar mounted on the beam engaging said nut, side 85 flanges on the beam engaging said lugs, means for lifting the beam and plate, and a motor operatively connected with the screw bar to shift the car laterally relative to the beam.

In testimony whereof I affix my signature in presence of two witnesses.

ALVA C. STEIN.
